TIE PINNING MACHINE AND METHOD

Philip de Anguera, Cincinnati, Ohio

Application May 11, 1949, Serial No. 92,588

11 Claims. (Cl. 144—31)

1

This invention relates to a machine and method for pinning the ends of timbers to preclude the development of open splits or cracks in said timbers during use, and the invention is particularly directed to a machine for applying spiral dowels to railroad cross ties, switch ties, bridge ties, or other similar timbers.

It is the principal object of this invention to provide an improved and efficient mechanism for producing pinned timbers in quantity. A typical timber which this improved mechanism is adapted to produce is a railroad tie having one or more spiral dowels forced entirely through the material of the tie adjacent each of its ends, and in positions substantially normal to the wood grain of the tie. Timbers with spiral dowels applied in this manner provide longer periods of service than nondoweled timbers, because the material of their ends is secured together by the dowels thus preventing the doweled timbers from developing splits and cracks which impair their usefulness and necessitate their replacement.

At present it is common practice to drive these spiral dowels into the ends of timbers with hammers or other impact tools before the timbers are placed in operative positions, or timbers may be doweled during placement in a particular structure after damaging cracks or splits have appeared therein. In either event, the work of driving dowels into the timbers has largely been performed by hand, which consumed considerable time, and as demand for doweled timbers has increased it is the particular object of the present invention to provide a means and method for supplying this demand in an economic and efficient manner.

In the present machine the timber is subjected to exceedingly high compressive forces while the dowels are driven into it and set in position whereby upon release of the pressure the dowels maintain the material of the wood in said compressed state until natural drying processes permit the dowels to assume normal conditions in the wood and thereafter preclude the development of cracks and splits therein.

A specific machine having an embodiment of the means set forth hereinbefore, and for the objects specified, is shown in the accompanying drawings and described in detail in the following specification, for illustration of the principles and characteristics of the invention, but without intent to limit the invention to such details.

In the drawings wherein like reference nu-

2

merals indicate similar parts throughout the several views:

Fig. 1 is a perspective view of the tie pinning machine.

Fig. 3 is an enlarged section taken on line 3—3 of Fig. 2.

10 Fig. 4 is an enlarged cross-section taken on line 4—4 of Fig. 2.

Fig. 5 is an enlarged elevational view of the pin feeding mechanism for the machine as it is depicted in Fig. 4.

15 Fig. 6 is a top plan view of the pin feeding mechanism illustrated in Fig. 5, parts thereof being broken away and illustrated in cross-section.

Fig. 7 is an enlarged section taken on line 20 7—7 of Fig. 6.

Fig. 8 is a section taken on line 8—8 of Fig. 6.

Fig. 9 is a cross-sectional view showing a detail of the pin pusher bar yoke of the pin driving mechanism.

25 Fig. 10 is a diagrammatic view of the electrically controlled, hydraulic system for my machine, and

Fig. 11 is a sectional view illustrating the manner in which a plurality of my machines are used for simultaneously pinning both ends of a timber, some operating parts therefor being shown diagrammatically.

The tie pinning machine has an elongated and relatively narrow base 15 comprising two transversely spaced I-beams 16 and 17 which have riveted or bolted to their end portions a lateral spacer 18. The opposed end of the base has a frame mounted thereon comprising a vertical plate 19 which is rigidly secured in place upon the base by a channel shaped gusset 20 having a pair of spaced triangular side plates 21 and 22 welded to the rear surface of the plate 19 and to a cross plate 23 extending between and mounted on the flange portions of the I-beams 16 and 17. Intermediate the ends of the base there is positioned a plate 24 which is rigidly and inflexibly secured thereon by a pair of I-beams 25 and 26 which have their lower flanges bolted or otherwise fixed to the upper flanges of the I-beams 16 and 17 respectively.

40 As illustrated in Figs. 1 and 2 the I-beams 25 and 26 of the frame are welded at their forward ends to the rear faces of the plate 24, whilst their rear ends are welded to plate 19. Longitudinal tie rods 27 and 28 extend between the upper ends

45 of the I-beams 25 and 26 and are rigidly secured to the rear faces of the plates 24 and 19 respectively. The tie rods 27 and 28 are welded to the rear faces of the plates 24 and 19 and to the rear faces of the I-beams 16 and 17 respectively.

50 As illustrated in Figs. 1 and 2 the I-beams 25 and 26 of the frame are welded at their forward ends to the rear faces of the plate 24, whilst their rear ends are welded to plate 19. Longitudinal tie rods 27 and 28 extend between the upper ends

of the plates 19 and 24 and cooperate with the I-beams 25 and 26 to form a rigid frame with the plates 19 and 24 that is capable of withstanding the high compressive forces developed therein by the machine during the clamping operation.

As clearly illustrated in Fig. 1 the machine has a centrally disposed tie clamping mechanism 29, a tie drilling device 30 at one end thereof, and a tie pinning mechanism 31 at its opposed end. These mechanisms are preferably automatically actuated by an electrically controlled, hydraulic system to successively receive and clamp the end of a railroad tie or other timber under a high compressing force, drill a plurality of holes through the compressed end of the timber and whilst it is under pressure drive spiral dowels into the predrilled holes.

Tie clamping mechanism

The plate 24, which is rigidly mounted upon the base and reinforced by the frame comprising the I-beams 25 and 26, the plate 19 and the tie rods 27 and 28, acts as the fixed jaw member for the tie clamping mechanism. Opposed to this plate is a movable jaw 32 supported in a vertical position for longitudinal reciprocating movement by a pair of spaced carrier wheels 33 and 34 which extend laterally from opposed lower sides of the jaw and have rolling engagement with the intermediate portions of the upper flanges for the I-beams 16 and 17 respectively. The movable jaw member is preferably constructed from a flat metal plate 35 reinforced along its vertical sides by heavy metal plates 36 and 37. The plate 35 has formed thereon rearwardly extending upper and lower studs 38 and 39 each provided with a threaded bore for receiving the threaded ends of longitudinal pull rods 40 and 41 respectively; said rods being locked in the studs by set nuts 42. The pull rod 41 passes through longitudinally aligned bearing holes formed in the plates 19 and 24 whilst the upper rod 40 is positioned above the frame. Both of the rods are connected across their rear portions by a yoke 43 which is connected thereto in a manner similar to the rod connection with removable jaw member 32. As illustrated in Fig. 2 the threaded ends 44 and 45 of the pull rods 40 and 41 pass through holes formed in the yoke and are adjustably secured to the yoke 43 by an opposed set of lock nuts 46. The yoke 43 may therefore be adjusted and secured in any suitable longitudinal position on the rods so that the machine may be adjusted to accommodate timbers of various thicknesses. The yoke 43 is provided with a center bore 47 into which is threaded the end of a piston rod 48 driven by a heavy duty hydraulic cylinder or motor 49, said cylinder being mounted in any suitable manner to the rear face of the plate 19. A piston 50 for the rod 48 is adapted for longitudinally directed, reciprocating movement within the cylinder 49 when fluid under pressure is alternately introduced into its ends. Upon introduction of fluid through a suitable port into the forward end of the cylinder, the piston 50 will move rearwardly thus forcing the yoke 43 rearwardly and moving the jaw 32 toward the fixed jaw member 24. It is contemplated that the hydraulic means for actuating the cylinder be adapted to exert a predetermined pressure that will set up a compressive force of from 8 to 10 tons on a timber positioned between the fixed jaw and movable jaw members, thus closing any cracks or splits that may be in the processed timber and holding said timber under

a material crushing force while it is being pinned.

Tie drilling device

The tie drilling device 30 comprises a slide plate 200 mounted for longitudinal reciprocating movement upon I-beams 16 and 17. As illustrated in Figs. 1, 2 and 3, each of the I-beams 16 and 17 have a series of rollers 201 and 202 respectively mounted thereon, which have their upper ends extending just above the upper flanges of the respective I-beams and which are in rolling engagement at these points with the undersurface of the slide plate 200. Fixed to and depending from each side of the plate 200 are guide bars 203 and 204, which cooperate with the series of rollers 201 and 202 respectively to provide accurately guided, longitudinal movement for the slide plate. The plate is secured to the movable jaw member for movement therewith by a yoke 205 extending from the central part of its forward end, and which is loosely pinned to a horizontal extension 206 formed on the lower end of the said jaw member.

The tie drilling spindle carriage is mounted for independent, longitudinal movement upon the plate 200 by a pair of spaced square tracks 51—52 secured to the plate by longitudinally spaced brackets 53 and 54. The tracks are adapted to support and guide the drill carriage for longitudinal movement toward and away from the end of the timber that is held under compression by the jaw members at the tie clamping station 29. The drill carriage comprises four corner posts 55 interconnected around their top portions by a series of cross members 56, whilst the intermediate portions of the posts are secured together by cross members 57. Opposed pairs of grooved wheels 58 are mounted to the lower ends of each of the cross members and each pair of wheels is adapted to have rolling engagement with the upper and lower surfaces of the tracks 51 and 52 so that the carriage will have smooth and accurate movement upon the plate 200. Drill spindle journals 59 and 60 are secured in guide blocks 61 each provided with opposed grooves for receiving and sliding along splines 62 formed on adjacent faces of the corner posts. The journals are vertically adjusted toward and away from each other by a vertical shaft 63 having oppositely directed threads cut in its upper and lower portions and which engage in internally threaded yokes 64 and 65 extending from the journals 59 and 60 respectively. The shaft 63 is precluded from axial movement by a shoulder 66 formed on its upper end which bears against an upper cap plate 67 for the carriage. The drill spindle journals are vertically adjusted by turning a hand wheel 68 secured to the upper end of the shaft 63. It will be noted that the oppositely threaded shaft not only adjusts the relative vertical positions of the drill spindle journals, but also supports the journals in their adjusted positions within the carriage.

As most clearly illustrated in Figs. 2 and 3 the drill spindles are rotated by pulleys 69 which are driven by an electric motor 70 mounted on a plate 71 which is pivoted at its upper end to the carriage. The motor has a V-belt drive 72 with the pulleys 69; the belt tension being adjusted by a screw 73 threaded in the lower end of the plate 71 and bearing against the carriage. A suitable housing 74 is mounted on the carriage and protects the pulleys and belt drive arrangement therefor.

Feed and return of the drill carriage is effected

by an hydraulic cylinder or motor 75 mounted to, and beneath the movable plate 200 and between the I-beams 16 and 17. The cylinder has a longitudinally movable piston 76 positioned therein which is connected to a piston rod 77. The outer end of the piston rod is secured to an arm 78 depending from a plate 79 that is welded or otherwise fastened to the lower extremities of the corner posts 55 of the carriage.

It will therefore be noted that the drill spindle carriage 30 is moved in unison with the movable jaw member 37 of the clamping mechanism 29 because the spindle carriage and its motor are mounted upon the movable plate 200 in turn secured by yoke elements 205-206 to the said clamping jaw. The spindle carriage also has independent feed and return motion relative to the set jaw members all for the purposes to be set forth after the hydraulic system for the machine has been explained in detail.

Tie pinning mechanism

The tie pinning mechanism 31 for the machine is designed to receive spiral dowels from a magazine and to simultaneously drive at least two of the dowels into prebored holes formed in the end of a timber, whilst the timber end is held under compression by the clamping device 29. The mechanism is illustrated in Figs. 4-7 in the drawings and comprises at least two pin guiding and receiving devices 80 and 81 mounted on the stationary jaw member or plate 24 for vertically directed, relative movement. The pin guiding and receiving devices 80 and 81 have somewhat similar structures and the same reference numerals will be employed for similar parts throughout the several views. Each device has a pin guide holder or base 82 provided with a centrally located open slot 83 (Fig. 7) for receiving a vertically positioned adjusting shaft 84 rotatably mounted in bearing plates 85 and 86 (Fig. 5) welded or otherwise fastened to the upper and lower ends respectively of a plate 87 that in turn is welded to the rear surface of the jaw member 24. The plate 87 is also supported by a gusset 88 that is welded to the outer surface of the plate and to the upper flange of the I-beam 26. The holders have routs milled therein for receiving nuts 89-90 which are oppositely threaded for cooperation with oppositely threaded portions 91-92 respectively formed on the shaft 84. The shaft is rotated for adjusting the relative positions of the members by a hand wheel 93 fixed on a shaft 94 which is journaled in the I-beam 26 and a bearing 95 depending from bearing plate 86. The shaft has fixed to its inner end a beveled gear 96 which meshes with a beveled gear 97 fixed to the depending end 98 of the oppositely threaded shaft 94. The pin guides and receiving devices are also guided for vertical movement by a pair of keys 99 secured to the inner surface of the plate 87 and which freely engage in grooves 100 formed in the sides of the members.

Rigidly secured to the opposite ends of the holders by screws or the like, are end plates 101 and 102 which have positioned between their front sides an upper pin guide bar 103 and a lower pin guide bar 104. The rear sides of the end plates carry a pair of spaced cross bars 105 and 106 which have mounted between them horizontally reciprocating heads 107. The heads have slots 108 formed therein for receiving the mounting portions of pin pusher bars 109 which have their free ends slidable in slots 110 formed between the adjacent faces of the bars 103 and 104.

As most clearly illustrated in Fig. 7 the holders 82 have grooves 111 formed in their inner faces in which are mounted pin guide blocks 112. The blocks 112 have pin receiving grooves 113 formed therein which have the sectional form of a portion of a triangle; the mouths of said grooves being wide enough to admit spiral dowels 114 thereinto from the vertically disposed dowel raceways 115 provided between the pin guide holders 82 and the pin guide bars 103-104. The complementary sections for the pin guide grooves 113 are formed on the dowel engaging portions 116 of the pin pusher bar 109.

The upper pin guiding and receiving device 80 differs from the lower device 81 in that its movable head 107 has secured thereto a slide plate 117 which has a gate or slot 118 formed therethrough at a point removed from its free end, whilst the member 81 differs from member 80 in that it has a pin stop bar 119 positioned in the lower end of its raceway 115. The outer sides of the movable heads 107 are connected together by a yoke 120 which has vertically extending slots 121 formed therethrough for permitting relative movement between the members 80 and 81 and for securing the members in adjusted position by set screws 122 which pass through the slots and are threaded in the movable heads 107.

With particular reference to Fig. 4 a spiral dowel magazine 123 is positioned upon the machine by legs 124 which are secured to the tie rods 27 and 28, said magazine having a slot 125 therein through which dowels pass in succession into a guideway 126 formed by oppositely disposed bars 127 and 128. The lower ends of the bars 127 and 128 are respectively secured in the pin guide holder 82 and the upper pin guide bar 103, and as most clearly illustrated in Fig. 7 the adjacent edges of said bars form a continuation of the raceway 115 for the upper device 80. The lower device has a pair of stub bars 129 extending upwardly from its pin guide holder 82 and its pin guide bar 103 respectively, said stub bars being in alignment with the raceway 115 in the upper device 80.

The pins or dowels in position within the raceways of the devices are moved laterally into their respective guides 113 and said guides closed by complementary guide portions 116 of pin pusher bars 109 when said bars are moved from their full line positions shown in Fig. 7 to their dotted line positions illustrated in said view. In normal inoperative positions the pin pusher bars 109 are in retracted positions beyond the raceways so that pins are permitted to move down the raceways by gravity until the lowermost pin is supported by a stop. With respect to the upper device 80 the stack of pins is supported by the end of the slide plate 117 so that the lowermost pin is below the path of the pin pusher bar 109 and maintains the next superjacent pin in position for lateral movement into the guide 113 by said bar. During this particular operational phase of the upper device 80 a single pin is in the raceway for the lower device 81 and rests therein upon the stop bar 119. Upon completion of the pusher bar feed strokes the aligned pins have been laterally moved into their respective guides and with reference to the upper device the said feed movement of the pusher bar provides lateral movement of the slide plate so that the gate 118 comes into registry with the raceway 115 thereby permitting the lowermost pin to fall into the raceway for the lower device and be held upon the pusher bar therefor until the latter's retraction when it will

assume a position upon the stop 119 awaiting the next pin driving operation. During pin driving operation the stack of pins are held in the raceway upon the pusher bar and upon retraction of said bar and the slide the lowermost pin will again rest upon the inner end of the slide holding the second lowermost pin in position to be pushed laterally into its pin guide by the pusher bar and the lowermost pin in position to fall through gate 118 into the raceway for the lower device 81.

The pusher bars are actuated by an hydraulic cylinder or motor 130 positioned on the frame and which has a drive bar 131 secured to its movable piston 132. The bar is loosely mounted to the long arm of a bell-crank lever 133 pivoted to the frame and which has its short arm pivotally secured to a drive shaft 134 bolted to a U-shaped frame 135 welded or otherwise secured to the outer surface of the yoke 120 for the movable heads 101. In order to preclude jamming of the dowels in the magazine one inclined bottom section thereof is made from a number of parallel strips 136 secured together by cross bars 137 and all of said bars pivoted centrally on a cross shaft 138 journaled in the end walls of the magazine. The outer end of the pivoted bottom section is pivotally secured to the upper end of the drive bar 131.

Pins positioned in the closed, triangularly shaped guides in the devices 80 and 81 are driven into the prebored holes formed in the ties by means of triangularly shaped pin pusher bars 139 mounted for relative vertical adjustment in a yoke 140 (Fig. 9) carried on the free end of a piston rod 141. The piston rod is driven by piston 142 which has a longitudinal working stroke within an hydraulic cylinder or motor 143 mounted at its rear end to the plate 19. As most clearly illustrated in Fig. 8 the plate 24 has a centrally disposed elongated slot 144 formed therein for receiving guide plates 145, said plates having triangular apertures 146 formed therethrough which may be vertically adjusted for alignment with the triangular guides 113 in the devices 80 and 81.

Machine control system and operation

Fig. 10 is a diagrammatic showing of an hydraulic system for operating the machine illustrated in Figs. 1-9, and has associated therewith an electric control means for the hydraulic system. The numeral 147 indicates an hydraulic pump, which takes fluid from a sump tank 148 and introduces it to a 4-way valve 149 through a pressure line 150. The valve 149 is normally in position to permit pressure fluid to pass through line 151 to the hydraulic motor 49 to operate the machine clamp and hold a tie end under tremendous pressure between stationary jaw 24 and movable jaw member 35. As the piston of the hydraulic motor 49 is moved into timber clamping position by the introduction of pressure fluid thereto by line 151, fluid is drained from the opposed end of the motor back to the sump tank 148 through a line 164, valve 149 and a drain line 259. When the fluid in the cylinder and line 151 reaches a predetermined pressure, a sequence valve 152 interposed in the line opens and permits pressure fluid to be introduced into a 4-way valve 153 through pressure line 154. The valve 153 is normally in position to direct pressure fluid introduced therein to the drill carriage motor 75 through line 155 to drive the carriage through its drill feeding stroke. Fluid is driven from the motor 75 during the carriage feed stroke through

line 156, which is connected to the valve 153 and which in turn returns said drain fluid to the sump tank by line 157. When the drill carriage reaches the end of its feed stroke, a limit switch 158, mounted on the machine base by a suitable bracket (Fig. 1), is closed by an extension on the carriage to energize a solenoid actuated pilot valve 159, which reverses the position of the 4-way valve 153 whereby pressure fluid from line 154 is introduced into the line 156 through a sequence valve 256 to the hydraulic motor 75 to return the drill carriage to its inoperative position, whereby fluid is driven from the opposed end of the motor 75 by way of line 155 and drain line 157. When the pressure has been built up in line 156 to a predetermined limit sequence valve 258 opens and permits the introduction of fluid from line 156 to the pin driving hydraulic motor 143 by means of line 160 whereby the pins are driven into the prebored holes made by the drills in the clamped timber. Fluid is drained from the opposite end of the motor 143 during the feed stroke of the pin driving plungers by a line 161, which is directed by the position of the 4-way valve 153 into the sump tank by line 157. When the pin driving motor 143 reaches its limit of motion, a moving part thereon operates limit switches 162 and 163, which simultaneously actuate the solenoid pilot valves 264 and 159 to reverse their respective 4-way valves 149 and 153 to respectively open the machine jaws by returning the clamp piston in motor 49 to its inoperative position and condition the four way valve 153 for the succeeding drilling operation. The pinned tie may thereafter be removed from the machine, and, as the clamp motor 49 reaches its inoperative position, a moving part thereon closes a limit switch 165, which may close down the machine or as illustrated in Fig. 10 it may close a circuit to a motor 166 for driving the tie feeding conveyor of the machine.

The pin feeding motor 130 is actuated to feed a pin into the pin guides 113 when fluid under pressure is introduced into the tie clamping motor 49 through a line 167 connected to said motor and to the pressure line 151. The pin feeding device is returned to its inoperative position when the pin driving device is being returned to its inoperative position through line 168, which is connected to the return pressure line 161 of the pin driving cylinder. It will be noted that the hydraulic cylinder is of the pressure differential type in that the piston has different effective working areas on its opposed sides due to the piston rod connection to one side thereof, which reduces the working area of the piston on that side. The presence of the same amount of fluid pressure on both sides of the piston through lines 167 and 168 will therefore return the piston to its said inoperative position for the next operational cycle.

With particular reference to Figs. 1 and 2, it will be understood that the limit stop 153 for the drill is fixed with respect to the stationary jaw member 24 and, that it functions to reverse the drill feed stroke just before the leading ends of the drills get through the railroad tie. The standard width measurement for railroad ties is not fixed, but may vary within certain limits and the point of entry of the drill and its stroke distance will therefore vary to some degree with each tie clamped in the machine for pinning. To begin the feed stroke of the drilling mechanism at approximately the point of entry into the tie the drill carriage and its feed and return mechanism are mounted on a plate 200 secured in

tandem to the movable jaw of the clamps whereby the leading ends of the drills are brought into close proximity to the work clamped by the jaw before the drill feed stroke is initiated.

The tie centering device

As illustrated in Fig. 11, two of my tie pinning machines may be positioned side by side and operated in unison to clamp, drill and pin both ends of a tie simultaneously. The tie is fed between the jaws of the machines by a conveyor 169, which has a number of spaced arms 170 thereon, which push the tie beyond the conveyor and into a position between the machines where it is supported by brackets 171 in approximate position for pinning. A limit switch 172 is then actuated by an arm 170 to open a circuit to conveyor motor 166 to stop the conveyor, said limit switch also operating a pilot valve to a 4-way valve 173, which introduces fluid under pressure to an hydraulic motor 174.

Hydraulic power for operating the centering device may be provided by opening the main pressure line 150 for one of the tie pinning machines and connecting the pump side to the 4-way valve 173 as indicated in Fig. 11. This motor actuates a centrally pivoted lever 175, which operates two arms 176 and 177 disposed on opposite ends of the positioned tie through links 178 and 179 respectively. The arms center and equalize the positioned tie so that the dowels are driven into the tie at the same distance from each end even though the tie may be a bit under or over length.

The motor 174 is returned to inoperative position after the tie is centered by contact of a part of the lever 175 with a limit switch 180 which actuates the pilot to reverse the 4-way valve 173. Upon return of the piston, pressure in the line 150, reaches a predetermined value, thereby opening a sequence valve 181, which directs oil under pressure to the clamping device 49 in the usual manner.

What is claimed is:

1. In a machine of the character described, an elongated frame, a stationary jaw member mounted upon the frame intermediate the frame ends, a fixed plate mounted upon one end of the frame, longitudinal structural members connecting the stationary jaw member and the fixed plate, a movable jaw member disposed above the frame for reciprocating movement toward and away from the outer face of the stationary jaw member, longitudinal pull rods secured to the jaw member and at least one of said rods journaled for axial movement through the said fixed plate and the stationary jaw member, a heavy duty fluid motor carried by the outer face of the fixed plate, a yoke connecting the ends of the pull rods and having an operative connection with said motor, at least two drilling devices mounted on the opposite end of the frame for operative movement through the movable jaw member to form holes through the timber compressed between the jaw members, a fluid motor for actuating the drilling means, at least two pin receiving and holding devices mounted adjacent the inner face of the stationary jaw member in longitudinal alignment with the drilling devices, longitudinal pin guides in the members, pin pusher rods mounted for reciprocatory movement within the guides, and a fluid motor carried by the inner face of the fixed plate and having an operative connection with the pin pusher rods and adapted upon actuation to drive pins from the guides into the pre-drilled holes

formed in the timber compressed between the jaw members.

2. The machine set forth in claim 1 characterized by the fact that the drilling devices are mounted on a carriage movable upon the frame, that the fluid motor for actuating the drilling devices is fixed on the carriage, and that said carriage is coupled to the movable jaw member.

3. A machine for transversely doweling the ends of a tie or other timber comprising a clamp having opposed jaws for compressing the end of the tie, means for opening and closing the clamp, a drill operable through one jaw of the clamp for drilling a hole in the tie and in the direction in which it is compressed and while it is under compression and movable from a position clear of the jaw through which it operates to a position where it enters a recess in the opposed jaw, and means at the outer face of the opposed jaw member opposed to the drill and in axial alignment therewith for driving a dowel into the hole which has been so drilled after the drill has been withdrawn therefrom and while the tie is still compressed.

4. A machine of the class described for doweling a piece of timber transversely of its length which comprises a pair of clamping jaws one of which is movable toward and away from the other, means for operating said jaws for clamping and releasing the portion of the timber to be doweled, means operable through one jaw of the clamp for drilling a hole through the clamped portion of the timber, and aligned means operable through the other jaw for forcing the dowel into the hole so drilled while the timber remains clamped between the jaws.

5. A machine of the class described for doweling a piece of timber transversely of its length, which machine comprises a pair of clamping jaws one of which is movable toward and away from the other, means for operating said jaws to clamp and release the portion of the timber to be doweled, drill means adjacent one jaw and movable toward and away from it and having a drill that passes through an opening in the jaw for drilling a hole entirely through the clamped portion of timber, dowel feeding means associated with the other jaw for delivering dowels one at a time to a dowel driving position, and means associated with the said other jaw for engaging a dowel in position to be driven and thrusting it through an opening in the jaw into the hole in the clamped portion of the timber which has been drilled by said drilling means.

6. A machine of the class described for doweling the end of a piece of timber which comprises a pair of clamping jaws one of which is movable toward and away from the other, means including a fluid motor for operating said movable jaw to clamp and release the portion of the timber to be doweled, means operable through one jaw for drilling a hole in the clamped portion of the timber engaged between the jaws, said drilling means being movable rectilinearly relative to the jaw through which it operates, means including a fluid cylinder for effecting a rectilinear movement of the drilling means, means aligned with the drilling means and operable through the other jaw for forcing a dowel into the hole which has been drilled in the clamped portion of the timber including a driver and a fluid motor for operating the driver, and a fluid system for controlling said motors to effect in a sequence the clamping of the jaws, the advance of the drilling means and the re-

11

traction of the drilling means relatively to the jaw through which the drilling means operates, and then the operation of the driver through an operating cycle followed by the opening of the clamping jaws.

7. A machine of the class described for doweling a piece of timber with transversely-extending dowels while it is compressed, which machine comprises a pair of clamping jaws one of which is movable toward and away from the other, means for operating said jaws to clamp and release the portion of the timber to be doweled, a plurality of drills operable through one jaw for simultaneously drilling parallel holes through the clamped portion of the timber engaged between the jaws, aligned means operable through the other jaw for simultaneously forcing a plurality of dowels into the several holes so drilled while the timber still remains clamped between the jaws, said drilling means being adjustable vertically to vary the spacing between the holes, said driving means being likewise adjustable vertically to maintain the position of alignment with the holes formed by the drilling means.

8. The method of doweling a tie or other timber with transversely-extending spiral dowels to prevent the same from splitting, which comprises subjecting the end of the tie to a transverse pressure of several tons, thereafter while the pressure is applied to the end of the tie, drilling a hole from one side of the tie transversely therethrough in the direction of the applied pressure, driving a spiral dowel into the hole so drilled in the tie from the opposite side thereof while the tie still remains under pressure, and releasing the pressure only after the driving of the dowel has been completed.

9. In a machine of the character described the combination of a base, a stationary jaw member on the base, a movable jaw member on the base, a drill carriage, a slide positioned upon the base for rectilinear movement thereon, means for attaching the slide to the movable jaw member, means for mounting the carriage on the slide for rectilinear movement, a motor on the slide having its working element connected to the drill carriage to provide feed and return strokes for the carriage, a control means for the motor positioned on the base a fixed distance from the stationary member, and actuating means for the control means fixed on the carriage in position to contact the control means when the drills on the carriage have reached the predetermined depth of their feed strokes.

10. In a machine of the character described the combination of a base, a stationary jaw mem-

12

ber on the base having a work clamping plate, a movable jaw member mounted on the base, and having a work clamping plate mounted on part of the movable jaw member for rectilinear movement toward and away from the plate, a motor mounted on the movable jaw member and having its working element in driving connection with the drill carriage to provide feed and return strokes for the carriage, a motor control means positioned on the base a fixed distance from the stationary jaw member, and an actuating means fixed on the carriage in position to contact the control means when the drill carriage has reached a predetermined position relative to the fixed jaw member.

11. In a machine of the class described the combination with a jaw member of a pair of vertically spaced pin guiding and receiving devices supported on the jaw member, vertically aligned pin raceways formed in the devices, and each supporting a single stack of pins, a separable pin guide in each device and each comprising a fixed longitudinal groove portion having a lateral opening into a raceway, a laterally reciprocated member having a pair of pin pushers each movable through a raceway to form with the respective fixed groove portion a closed pin guide, stop means beneath each raceway for supporting a stack of pins with a pin in the stack disposed opposite the opening in a groove, means connecting the stop for the uppermost pin stack with the reciprocated member to move said stop out of the raceway when the member is effective to close the pin guide, said uppermost stop being located beneath the groove opening in the raceway a distance to position the lowermost pin in the stack below the said groove opening, a pin driving bar reciprocable within each closed groove, and means for operating the pin driving bars when the laterally reciprocated member has its pin pushers in operative positions closing the openings.

PHILIP DE ANGUERA.
